UNITED STATES PATENT OFFICE.

HENRY STERLING CHAPIN, OF ROCKVILLE CENTER, NEW YORK.

APPARATUS FOR TREATING PIPE-BOWLS.

1,076,867.

Specification of Letters Patent.

Patented Oct. 28, 1913.

Application filed May 31, 1912. Serial No. 700,578.

To all whom it may concern:

Be it known that I, HENRY S. CHAPIN, a citizen of the United States, and resident of Rockville Center, in the county of Nassau and State of New York, have invented certain new and useful Improvements in Apparatus for Treating Pipe-Bowls, of which the following is a specification.

My invention relates to the manufacture 10 of pipes for smoking tobacco.

When an ordinary wooden pipe such as a brier or imitation brier is first smoked the natural resins and sometimes artificial coloring matter such as shellac, oil or other 15 finishing material are distilled or burned and the products of combustion drawn in with the smoke of the tobacco. The flavor is sickening and to such an extent that many smokers judging from their first experience 20 with a new pipe believe that they cannot smoke a pipe at all although from motives of economy and because of other attractive features of pipe smoking they would be very glad to adopt the use of a pipe. Furthermore, when an ordinary wooden pipe is 25 "broken in" the first fresh power of absorption which makes the pipe smoke sweet is gone and the cells of the wood are filled or partially filled with nicotin and other 30 substances long before the taste of the raw wood or shellac or varnish or other finishing material disappears. I have found that these disagreeable features may be avoided 35 by burning the interior of the bowl suffi- ciently to remove unpleasant taste-producing elements from the inner surface of the wood by means of an open flame or a suitably heated device. This does not affect the 40 mechanical strength of the bowl and leaves the inner surface absorptive but free from nicotin.

It is the object of this invention to provide simple, inexpensive and easily operated mechanism for burning the interior of the 45 pipe bowl.

The invention consists preferably of a suitably heated device adapted to fit the interior of a pipe bowl. A guard is arranged to receive the pipe bowl and direct 50 it toward the burning element and the parts are so arranged and constructed as to avoid scorching the edge of the bowl. A holder may also be provided and with means for rotating the bowl while on the burning 55 element.

Two forms of the invention are illustrated in the accompanying single sheet of drawings.

Figure 1 is a vertical side view and partial section showing one form of apparatus 60 embodying the improvements of my invention. Fig. 2 is a similar view of another form. Fig. 3 is a sectional view showing a bowl in place in the guard and on the burning element.

The burning element 1 is shaped according to the interior of the bowl to be burned and is heated preferably redhot for instance, by means of the flame of a blowpipe 2. A guard 3 is arranged to receive a 70 pipe bowl 4 and to guide it toward the burning element. In the form shown in Fig. 1 the guard is carried by an arm 5 pivoted at 6 so that when the bowl is inserted in the guard and moves forward with it, it will 75 be automatically centered on the burning element. A spring 7 normally holds the guard arm against the stop 8 away from the burning element so that the guard is not heated but can cool off readily by radiation. 80 This guard not only centers the bowl and directs it toward the burner but prevents the burner from scorching the edge of the bowl and destroying its new appearance. In the form shown in Fig. 1 the carrier 9 85 also pivoted at 6 has a series of spring gripping fingers or jaws 10 for holding the bowl of the pipe so that a pipe bowl may be inserted in the grippers 10 and when the arm 9 is lifted toward the right the bowl 90 will engage in the guard 3 and the two elements travel together toward the burning element 1. In order to enable the operator to readily rotate the bowl 4 when it is in place on the burning element to facilitate 95 more uniform burning, the grippers or jaws 10 may be carried by a shaft 11 rotatable in the outer end of the arm 9 and having a crank handle 12 for rotating it.

In the form shown in Fig. 2 the burner 100 20 is electrically heated by means of a resistance coil 21. The guard 22 shaped on its interior to receive the pipe bowl 23 is mounted to slide on or with a rod 24. A spring 25 holds the guard normally in the position of Fig. 2. When a pipe bowl is inserted for instance by hand into the guard 22, the bowl and guard are forced on to the burner at which time the pipe bowl may be rotated to insure a more uniform burning 105 110

action. When the pressure on the bowl is removed the spring 25 throws the guard back to its normal position.

Preferably the head of the burner is of less depth than the bowl so that there is less danger of burning the edge of the bowl as shown in Fig. 3. Further to protect the parts I may provide suitable thermal insulation such as asbestos 30 and 31. This avoids scorching the edge or exterior of the bowl and also serves as a guard to protect the operator.

While I have shown the pipe bowl and guard as movable toward the burner and the burner as stationary and this is the preferred form, it is obvious that the burner may be movable toward the guard or toward the pipe bowl. It should also be understood that ventilating and air circulating apparatus may be used in conjunction with this apparatus for removing the products of combustion in a manner analogous to the removal of dust or dirt from the vicinity of machines such as are commonly employed in shaping and finishing pipe bowls and other devices.

What I claim is:—

1. Pipe treating apparatus comprising a relatively stationary burner for charring the interior of a pipe bowl and a movable guard to receive a pipe bowl and adapted to surround the burner and limit the movement of the bowl.

2. Apparatus for treating pipes comprising a burner for charring the interior of a pipe bowl and a movable device adapted to receive a pipe bowl and guide it on to the burner and a spring for automatically retracting said guide device from said burner when released.

3. Pipe treating apparatus comprising a burner having a head of a size somewhat less than the interior of the bowl to be treated so as to fit into and char the interior of the bowl and thermal insulation means surrounding the base of the head and a guard for limiting the movement of the pipe bowl.

4. Pipe treating apparatus comprising a burner for charring the interior of the bowl and a device adapted to receive and guide a pipe bowl when out of engagement with the burner and means for directing the movement of said device in line with the burner whereby the bowl in the device may be moved up to and on to said burner.

5. Pipe treating apparatus comprising a burner for charring the interior of the bowl

and a movable guard for receiving the bowl and preventing the edge and the outer surface of the bowl from being charred.

6. Pipe treating apparatus comprising a burner for charring the interior of a pipe bowl and an insulating device for fitting the edge of the pipe bowl and preventing the burner from charring the edge of said bowl.

7. In a pipe treating apparatus, a burner head shaped to correspond with the interior of the bowl of the pipe to be treated and of less depth than the depth of the bowl to thereby fit into and char the interior of the bowl and thermal insulating means around the base of the head.

8. In a pipe treating apparatus, a burner head shaped to correspond with the interior of the bowl of the pipe to be treated and of less depth than the depth of the bowl to thereby fit into and char the interior of the bowl, thermal insulating means around the base of the head and a guard for the edge of the pipe bowl.

9. Pipe treating apparatus comprising a burner head for burning the interior of a pipe bowl and a guard device for the pipe bowl in which the pipe bowl may be given a motion of rotation relative to the burner head.

10. Pipe treating apparatus comprising a relatively stationary burner head shaped to fit the interior of a pipe bowl whereby to char the inner walls of a pipe placed over the said burner, a relatively movable guard arranged to receive and center the pipe bowl with respect to the burner and means directing the movement of the guard toward the burner to thereby guide the pipe bowl into position over the burner.

11. Pipe treating apparatus comprising a burner for charring the interior of the pipe bowl, a rotatable support for the pipe bowl adapted to be moved to bring the pipe bowl into position at said burner and means for guiding said support.

12. Pipe treating apparatus comprising a burner for charring the interior of the pipe bowl, a rotatable support for the pipe bowl adapted to be moved to bring the pipe bowl into position at said burner, a guard device adapted to be moved with said support, and means for guiding said support.
